UNITED STATES PATENT OFFICE.

VICTOR H. JENNINGS, OF WORCESTER, MASSACHUSETTS, ASSIGNOR TO UNIVERSAL PATENTS COMPANY, OF WOONSOCKET, RHODE ISLAND, A CORPORATION OF RHODE ISLAND.

MACHINE-GUN BELT AND THE LIKE.

1,283,412.

Specification of Letters Patent. Patented Oct. 29, 1918.

Application filed April 12, 1917. Serial No. 161,433.

To all whom it may concern:

Be it known that I, VICTOR H. JENNINGS, a citizen of the United States, residing at Worcester, in the county of Worcester, State 5 of Massachusetts, have invented a certain new and useful Improvement in Machine-Gun Belts and the like, of which the following is a specification, reference being had therein to the accompanying drawings.

10 The invention is an improvement in machine-gun belts and other carriers of the same general character and construction as those used as machine-gun belts. It provides in novel and improved manner for the 15 manufacture of the said belts with the cored or beaded effect which is desired at one edge of such a belt or carrier. Also, with the thickening which is desired alongside the cords or beads for the purpose of 20 compensating, in the case of a machine-gun belt, for the smaller diameters of the bullets of the cartridges occupying the loops of the belt or carrier as compared with those of the shells of the cartridges. In addition it facilitates 25 the said manufacture, and enables uniform results to be attained.

The invention has reference, more particularly, to carriers of the type composed of two strips of flexible material, usually 30 woven cloth, placed back to back and secured together on transverse lines at intervals so as to form loops opening from edge to edge of the carrier and adapted to contain cartridges or other inserted articles.

35 In accordance with the invention, a carrier of the said type is made of two strips, each strip primarily of a width greater than the body of the carrier and formed with or having attached thereto a bead, 40 cord, or rib extending longitudinally thereof at a distance from one edge corresponding substantially with the width of hem desired, and each strip folded or turned transversely upon itself on a longitudinal line determined by the said bead, cord, or rib, with the infolded or inturned marginal portion secured in place so as to constitute the said hem. Machine-gun belts have been made heretofore by combining two strips, each 45 folded transversely upon itself around a loose or unattached cord which is guided into place at the time of folding the strip and securing the folded-over portion in

place. The invention is distinguished, however, by the fact of employing strips each 55 formed with or having fixedly attached thereto prior to the folding or turning a bead, cord, or rib, as aforesaid, adapted to determine the line of fold.

The invention is illustrated in the drawings, which show a number of embodiments of the characteristic feature of the invention, namely a carrier-strip or web formed with or having attached thereto a bead, cord, or rib extending longitudinally thereof at a distance from one edge of the said strip or web.

Figure 1 of the drawings is a perspective of a short portion of the length of a belt or carrier such as is used in a machine-gun, with cartridges occupying some of the loops of the said belt or carrier.

Figs. 2, 3, 4 and 5, respectively, show short lengths of carrier-strips or webs woven with beads, cords, or ribs according 75 to the invention, a number of different kinds of beads, cords, or ribs being represented in the various views.

The machine-gun belt or carrier shown in Fig. 1 is, in general, of a known type of construction, namely, composed of two woven strips or webbings 1, 1, laid back to back and bound together by pairs of metal clips 2, 2, and 3, 3, etc., the two clips constituting a pair being placed against the opposite 80 outer sides of the two strips or webbings and being fastened together with the strips or webbings between them by means of hollow rivets or eyelets 4, 4, etc. The distance between one pair of clips and the next corresponds with the size of loop required between the two strips or webbings for the 85 reception of a cartridge 5. Certain of the pairs of clips, namely those marked 3, 3, occurring at regular intervals in the series of 90 clips, are of greater length than the others and project beyond the enlarged or beaded margins of the belt or carrier, to serve as guides, as usual. In Fig. 1 the beaded or corded effect is produced by means of 100 bunches 6, 6, of warp-threads, and 7, 7, are the folded-over or turned-over marginal portions or hems of the strips 1, 1. By means of the said hems compensating 105 thickenings adjacent the corded or beaded margin of the belt or carrier are produced.

Lines of stitches fastening such folded-over or turned-over marginal portions in place are shown at 8, 8.

In accordance with the invention and as indicated above, each strip or webbing 1 is formed with or has attached thereto a bead, cord, or rib extending longitudinally thereof at a distance from one edge corresponding with the contemplated width of fold-over or hem. Fig. 2 shows a bead, cord, or rib that consists of a bunch 6 of warp-threads bound by weft-threads 9, 9, to one face of a strip or webbing 1. Fig. 3 shows one that consists of a single strand or cord 6^a of the required size which is bound similarly to a strip or webbing 1^b by weft-threads 9, 9. Fig. 4 shows one that is formed by producing a longitudinal tube in a strip or webbing 1^c, by weaving the latter double, *i. e.* in two separate plies, for a portion of its width, and inclosing a bunch of warp-threads 6^b between such plies in the process of weaving. As will be apparent a single strand or cord like that indicated at 6^a in Fig. 3 might be inclosed between the two plies instead of the bunch of warps. Fig. 5 shows a longitudinal rib 6^c formed upon the strip or webbing 1^d by an increase in the number of plies composing the strip or webbing, or it might be through the use of thicker warp-threads, without any inclosed stuffer-warps or cord. The beads, cords, or ribs may be formed upon or attached to the strips or webbings in still other ways.

35 A strip or webbing formed with or having attached thereto a bead, cord, or rib at a distance from one edge corresponding with the contemplated width of fold-over or hem may readily be folded, doubled, or turned-over upon itself along a longitudinal line determined by the said bead, cord or rib. This will insure that the folded-over, doubled-over, or turned-over part or hem

will be of the correct width, as well as give a better finished article than one made by the old method in which a fold is turned in the usual way and a cord is run in on the stitching machine.

What is claimed as the invention is,—

1. A belt or carrier made of strips secured together at intervals, forming loops or pockets between them, each strip having attached thereto a bead, cord, or rib at a distance from both edges thereof, and being infolded transversely upon itself on a longitudinal line determined by the bead, cord, or rib, to produce a thickened portion of the belt or carrier, with the folded-over portion secured in place by applied fastening-means.

2. A belt or carrier made of strips secured together at intervals, forming loops or pockets between them, each strip woven with a bead, cord, or rib at a distance from both edges thereof, and being infolded transversely upon itself on a longitudinal line determined by the bead, cord or rib, to produce a thickened portion of the belt or carrier, with the folded-over portion secured in place by applied fastening-means.

3. A belt or carrier made of strips secured together at intervals, forming loops or pockets between them, each strip formed with an interval bead, cord, or rib at a distance from both edges thereof, and being infolded transversely upon itself on a longitudinal line determined by the bead, cord or rib, to produce a thickened portion of the belt or carrier, with the folded-over portion secured in place by applied fastening-means.

In testimony whereof I affix my signature in presence of two witnesses.

VICTOR H. JENNINGS.
